UNITED STATES PATENT OFFICE

NORMAN L. SNOW AND ALBERT W. HONYWILL, JR., OF DETROIT, MICHIGAN, ASSIGNEE
TO DIAMOND POWER SPECIALTY CORPORATION, OF DETROIT, MICHIGAN, A COR-
PORATION OF MICHIGAN

BOILER CLEANER

Application filed July 27, 1925. Serial No. 46,451.

The invention relates to boiler cleaners and has for its object the improved apparatus as more fully hereinafter set forth.

Referring to the drawings in which like reference characters indicate corresponding parts:

Figure 1 is an elevational view partly in cross section of a boiler cleaner showing my invention applied thereto;

10 Figure 2 is a view along 2—2 of Figure 1 with a portion of the valve casing broken away;

Figure 3 is a sectional view showing in detail the alarm device;

15 Figure 3A is a sectional view on the line 3A—3A of Figure 3;

Figure 4 is a fragmentary view in section illustrating my improved construction for preventing leakage around the valve stem;

20 Figure 5 is a view corresponding to Figure 4 showing a slightly modified construction; and

Figure 6 is a fragmentary sectional view showing a valve construction adapted to 25 admit cleaning fluid in stages to the blower element.

In the boiler cleaner or blower head assembly shown in Figures 1 and 2, reference character 10 indicates the rotatable blower element extending through the boiler wall 11 and provided with one or more cleaning fluid discharge nozzles 12. 13 is the goose-neck for supplying the cleaning fluid such as steam or the like to the blower element. 14 is the valve controlling the passage of cleaning fluid through the goose-neck, this valve being located within the valve casing or steam pot 15 at the lower end of the goose-neck. The blower element is adapted to be rotated by suitable means including reduction gearing comprising in the present instance the chain wheel 16, the pinion 17 and the gear 18 meshing with the pinion. The valve 14 is actuated upon rotation of the blower element by suitable means such as the lever 19 pivoted at 20 upon the lug 21 extending upwardly from the valve casing and having its lower edge engageable with the valve stem 22 which extends upwardly through the valve casing. This lever

is actuated by a suitable cam 23 which latter rotates with the blower element.

24 is a cylindrical casing carrying the alarm or whistle 25, this casing communicating through pipe or passage 26 with the supply of cleaning fluid preferably at a point such as at the valve chamber 15 as shown in Figure 2.

Referring to Figure 3 the construction of the chamber 24 is shown in detail whereby means is provided automatically actuatable a predetermined length of time following the opening of the valve for advising the operator of the passage of cleaning fluid to the blower element.

In one end of the cylinder 24 is threaded a thermostatic element 27. Lock nut 28 is provided to fix the position of the thermostatic element in the end of the cylinder or chamber 27. Surrounding substantially three sides of this thermostatic element and separated therefrom by wall 28

is a chamber 29 communicating through a regulating valve 30 with the cleaning fluid supply pipe 26. Threaded in the other end of the chamber 24 is a bushing 31 provided with a passage 33 leading to the interior of the chamber 24. A T fitting 32 is threaded into a lateral extension 29' of the chamber 29 and this fitting is provided with the T passage 32'. One branch of this T passage communicates with the chamber 29, while a second branch of the same communicates with passage 33. Bushing 34 is threaded into the end of chamber 24 and carries an alarm or

other indicating means such as the whistle 25. Passage 35 relatively smaller than the passage 33 is provided through the bushing 34 and communicates with the third branch of T passage 32' whereby cleaning fluid is admitted from passage 32' and conducted to actuate the whistle. The element 27 terminates in a cone-shaped portion 36 which, when the element 27 expands, is adapted to

contact with and close the passage 33. 37 is an opening which is adapted to vent the valve chamber 38 to the atmosphere. One or more openings 39 in the chamber A are provided leading from the atmosphere to the annular

space 40 around the thermostatic element 27.

30 35 40 45 50 55 60 65 70 75 80 85 90 95 100

The openings 39 may be covered or closed to any desired degree by the closures 41, which are adjustable slidably across the openings 39.

5 To facilitate assembly of the fitting 32 in the cylinder 24, the threaded portion of the cylinder adapted to receive the bushing 31, is extended downwardly as illustrated in Figure 3 of the drawing, so that the bushing 31 may, during the assembling operation, be temporarily positioned below its normal position as shown in Figure 3 of the drawing. Thus with the bushing 31 threaded downwardly to the position shown in dotted lines in the drawing and with the bushing 34 removed, the fitting 32 may be rotated to thread the same into the extension 29'. After the fitting 32 has been correctly positioned within the cylinder 24, the bushing 31 may be threaded upwardly until the top of the same abuts one end of the fitting 32 after which the bushing 34 may be threaded into position and into abutting engagement with the other end of the fitting 32.

25 In operation the attendant actuates the wheel 16 to cause rotation of the blower element 10 and the simultaneous unseating of the valve 14 to supply the cleaning fluid through the goose-neck 13 to the discharge nozzles 12. A portion of the cleaning fluid will flow through the passage 26 and pass through valve 30 and into the chamber 29 at a rate determined by the setting of the valve 30. From chamber 29, the cleaning fluid 35 will pass through passage 32, passage 33 and thence to the atmosphere through the passage 37. The small amount of cleaning fluid which would pass through the passage 35 to the whistle 25 would not be at a sufficient pressure to operate the whistle. This result is accomplished by reason of the relative sizes of the passages 33 and 35, the former passage being of considerably greater capacity than the latter. As the thermostatic element 27 40 is heated by the fluid which substantially surrounds it in the chamber 29, it will expand and the cone-shape valve 36 will seat on bushing 31, thus closing the opening therein to the passage 33. This will shut off the fluid to the valve chamber 38 and passage 37 and will cause the full pressure of the fluid to pass through passage 35 to the whistle 25 so as to cause the same to sound. The sound of the whistle will preferably continue until 45 the cleaning fluid is shut off the system. The function of the openings 39 is to allow air to circulate around the thermostatic element 37 to prevent undue heating thereof. These 50 openings also serve as a means of escape for any fluid which might leak past the valve 36 into the space 40. By adjusting the valve 30 and the closures 41, the whistle may be caused to function after any desired length 55 of time following the actuation of the valve

14 which supplies the cleaning fluid to the blower element.

By reason of the foregoing apparatus the boiler cleaner may be operated for a predetermined length of time without sounding of the whistle. Should the operator leave the boiler cleaner with the cleaning fluid turned on, the arrangement will automatically sound after a predetermined interval. The delay acting arrangement is also useful in advising the attendant of the expiration of a predetermined period of operation of boiler cleaner, thus efficiently operating the same.

Referring to Figures 4 and 5, we have disclosed means for preventing leakage around the valve stem. Attached to the valve stem 22^a is a valve disc 42 held in place by a nut 43. This valve is adapted to seat on the valve seat 44 as will be readily understood. A recessed bushing 45 is threaded into the upper wall 46 of the valve chamber or steam pot 15. A suitable opening is provided in the bushing 45 permitting movement of the valve stem 22^a. 47 is a plate mounted in a notch 48 located adjacent the outer end of the valve stem. Fixedly attached to this plate and to the bottom of the recessed bushing 45 is a flexible element 49 in the nature of a bellows or siphon. The flexible bellows 49 will readily contract and expand with the movement of the valve stem maintaining at all times a fluid tight joint between the valve stem and valve chamber. A spring 50 may be mounted exteriorly of the element 49 and may act on an extension of the plate 47 for normally holding the valve closed. Small openings 51 may be provided in the bottom of the bushing 45 for preventing the formation of a vacuum which might render the operation of the valve stem difficult.

In the modified construction shown in Figure 5 the arrangement of parts is substantially the same as shown in Figure 4. In this figure, however, the plate 47^a is adapted to be held in the notch 48^a of the valve stem 22^b by reason of a nut 52. Also in this construction, an additional bearing 53 is provided for guiding the valve stem 22^b.

Referring to Figure 6 we have shown a boiler cleaner constructed to admit cleaning fluid successively in increasing amounts or in stages to the blower head. For accomplishing this result we have provided a valve formed of a plurality of elements which are adapted to function in stages as aforesaid. In this figure the steam pot or valve casing, or chamber 15 is provided with a valve seat 54 provided with the opening 55 affording passage of cleaning fluid. 56 is a seat member normally held in seated position adjacent the seat 54 so as to close the opening 55 by reason of the springs 57 which act against the plates 58^a carried by bolts 59 slidable through the seat 54 for engagement with the seat member 56. These bolts are relatively

fixed to the seat member 56 by reason of the nuts 60. The seat member 56 is also formed with an opening 57' and an offset portion 58 providing a sliding bearing for the valve stem 22°. The portion 58 is also provided with a plurality of openings 61 which communicate with the opening 57' for conducting cleaning fluid therefrom. The seat member 56 is adapted to perform the double function of a valve and valve seat since it regulates the passage of cleaning fluid through the opening 55 and also forms a seat for a valve 62 which is secured to the lower end of the valve stem 22°. 63 is a projection carried by the valve stem for engagement with the portion 58 for moving the member 56 as described hereinafter.

In operation when the valve stem 22° is depressed by the trigger 19 the valve 62 is unseated from the member 56 thereby causing cleaning fluid to pass through the openings 57 and 61 to the steam pot 15. As the valve stem is so depressed through the action of trigger 19, the projection 63 of the valve stem comes into contact with the portion 58 of the seat member 56 causing the latter member in turn, to be unseated from the seat 54 thereby providing additional opening for the passage of cleaning fluid from the supply line into the steam pot. During the movement of the seat 56 away from the seat 54, the springs 57 are compressed. As the valve stem rises during the valve closing period the springs 57 first return the member 56 to its seat 54 and as soon as the projection 63 passes beyond the point of contact with the portion 58 the valve 62 is drawn to its seat to close the opening 57 by reason of the spring 64. By varying the relative proportions of the valves and cleaning fluid passages, or openings, any desired ratio of cleaning fluid flow during the two stages of the valve opening may be obtained. It is also obvious that the time intervals of the two stages may bear any desired relation.

What we claim as our invention is:—

1. In a boiler cleaner, a blower element, provided with a nozzle adapted to discharge cleaning fluid, means for supplying a cleaning fluid to said nozzle, a valve controlling the supply of cleaning fluid, means for actuating said valve, means automatically actuated a predetermined length of time following the actuation of the valve for advising the operator of the passage of cleaning fluid to said nozzle, and means for regulating the said time interval.

2. In a boiler cleaner, a blower element provided with a nozzle adapted to discharge cleaning fluid, means for supplying a cleaning fluid to said nozzle, a valve controlling the supply of cleaning fluid, means for actuating said valve, an alarm, and means automatically responsive to the passage of cleaning fluid a predetermined length of time fol-

lowing the actuation of said valve for sounding said alarm, and means preventing sounding of the alarm during the said time interval following the actuation of the valve.

3. In a boiler cleaner, a blower element 70 provided with a nozzle adapted to discharge cleaning fluid, means for supplying a cleaning fluid to said nozzle, a valve controlling the supply of cleaning fluid, means for actuating said valve, an alarm, and means automatically responsive to the passage of cleaning fluid a predetermined length of time following the actuation of said valve for sounding said alarm, means preventing sounding of the alarm during the said time interval following the actuation of the valve, and means regulably controlling the said time interval.

4. In a boiler cleaner, a blower element 85 provided with a nozzle adapted to discharge cleaning fluid, means for supplying a cleaning fluid to said nozzle, a valve controlling the supply of cleaning fluid, means for actuating said valve, a whistle, and means automatically responsive to the passage of cleaning fluid a predetermined length of time following the actuation of said valve for supplying cleaning fluid to said whistle for actuating the same, and means preventing sounding of the whistle prior to the expiration of said 95 time interval.

5. In a boiler cleaner, a blower element provided with a nozzle adapted to discharge cleaning fluid, means for supplying a cleaning fluid to said nozzle, a valve controlling 100 the supply of cleaning fluid, means for actuating said valve, a whistle, means automatically responsive to the passage of cleaning fluid a predetermined length of time following the actuation of said valve for supplying cleaning fluid to said whistle for actuating the same, means preventing sounding of the whistle prior to the expiration of said time interval, and means regulably controlling the 105 said time interval.

6. In a boiler cleaner, a blower element provided with a nozzle adapted to discharge cleaning fluid, means for supplying a cleaning fluid to said nozzle, a valve controlling 110 the supply of cleaning fluid, means for actuating said valve, and means automatically actuated a predetermined length of time following the actuation of the valve for advising the operator of the passage of cleaning fluid to the said nozzle.

7. The combination with a blower element, and means for supplying a cleaning fluid to said element, of an alarm, and means operable to effect an actuation of said alarm after the cleaning fluid has been supplied to said element for a predetermined period of time.

8. The combination with a blower element, and means for supplying a cleaning fluid to said element, of an alarm, and means operable to effect an actuation of said alarm after the 130

cleaning fluid has been supplied to said element for a predetermined period of time, said means including a valve and means for automatically actuating the said valve.

- 5 9. The combination with a blower element, and means for supplying a cleaning fluid to said element, of an alarm, and means operable to effect an actuation of said alarm after the cleaning fluid has been supplied to said
10 element for a predetermined period of time, said means including a valve and a thermostat for actuating the said valve.

In testimony whereof we affix our signatures.
